UNITED STATES PATENT OFFICE

WILLIS W. HALE, OF CLEVELAND, OHIO

WIENER STEAMER

Application filed May 31, 1930. Serial No. 458,221.

This invention has to do with steam cooking appliances for cooking wiener sausages, and the like, and refers more particularly to an appliance of this class provided with compartments, in any one of which the wieners to be served are sequestered from those being prepared for future use.

In connection with this type of wiener steamer, the chamber is partitionally divided and is provided with two distinct closures. The inner closure is so constructed that it forms a closure and indicator for one of the compartments in which sausages are being cooked when the outer closure has been removed to obtain access to wieners in the other compartment, the latter having already been cooked.

The closure may be bodily removed and reversed to form a cover or closure for any one of the compartments. The inner closure is mounted on the top of the wall forming the chamber, and the outer is so constructed that it is surmounted on and cooperates with the inner closure.

A special object in view is to utilize the inner closure not only as a closure means, but also to act as a brace for the separating partition of the compartments.

Like reference characters indicate like parts throughout the drawings.

In the accompanying drawings:

Figure 1 is a view in front elevation, of a wiener steamer comprising an inner closure embodying my invention, portions being broken away.

Figure 2 is an enlarged perspective view of an inner closure showing its construction.

Figure 3 is a sectional view taken on line 1-1 of Figure 2.

Now referring to the drawings for a full understanding of the invention and its merits, in conjunction with the following description, it will be observed that my steamer appliance comprises the vessel or chamber A which is preferably, though not necessarily, circular, being made of glass so that its contents, usually sausages or similar articles of food, may be visible to the purchasing public. The chamber or vessel A of somewhat cylindrical form is carried by a base B which is

preferably an electric heater of some type, though other kinds of heating means might be used within the purview of the invention. The vessel or chamber A is removable relatively to the base when it is desired to clean the whole appliance or otherwise handle the same as for shipment, etc. Since the construction of the vessel A and the base are not important to the present invention, they will not be further described.

It suffices to state that I contemplate dividing the chamber A into two compartments preferably, though it might be divided into a greater number of compartments. For the above purpose I utilize a partition 3 which permits of separation of the wieners or sausages which are in process of being cooked from those which may be already cooked and ready to dispense. The partition 3 is detachably secured by means not shown, to a plate carried by the base B and upon which the vessel or chamber A is supported. At its upper end the partition 3 terminates in a plane about that horizontally intersecting the upper end of the chamber A.

Now it is desirable that in the use of my appliance some indicating means be employed to advise the user in which one of the compartments designated 6 and 7 at opposite sides of the partition 3, the sausages in process of cooking are retained, and which one of the compartments contains those sausages that are cooked and ready to dispense. With the above in mind, therefore, I utilize an inner closure 4, the closure portion of which is about semi-circular in form and comprises a circular rim 8 which conforms with the circular formation of the upper end of the chamber or vessel A. At its central portion, considering central with relation to its meaning appertaining to the vessel A, the closure 4 is formed with a downwardly extending flange 10 adapted to contact with one side of the upper end of the partition 3, said flange having struck out therefrom a projection 11 disposed in a plane spaced from the flange and adapted to engage over and interlock with the upper end of the partition, in cooperation with the flange 10. Suitable vent holes 12 will be pro-

vided in the closure 4 for the usual purpose. Disposed above the inner closure 4 is the outer closure 5 having a suitable handle 5a affixed thereto in any substantial manner. 5 The closure 5 is of circular form and formed with a flange or rim 5b to engage over the circular flange or rim 8 of the inner closure. Now it will be apparent that if wieners or similar articles of food are being cooked in 10 the compartment 6 it is desirable that the upper end of this compartment be kept closed when the cover 5 is removed to have access to the vessel A respecting its other compartment 7 in which already cooked 15 sausages may be disposed prepared for dispensing to the public. When a supply of sausages in the compartment 7 is substantially exhausted, having been dispensed we will say, the compartment is refilled with a 20 fresh supply of sausages or similar articles of food, and then the inner closure 4 is reversed from the position of Figure 1 so as to extend over the compartment 7 and close the latter, while the fresh supply of sausages is 25 being cooked. The sausages after this time are dispensed preferably from the compartment 6 wherein a suitable supply has been previously cooked, in an obvious manner.

Under the foregoing conditions, the closure 4 affords an advantageous indicator assisting the user of the appliance to determine from which one of the compartments 6 and 7 he should dispense the cooked articles of food. Moreover, the closure 4 is advantageous in retaining the steam or heat in one of the compartments 6 and 7 in which the cooking operation is going on, notwithstanding the cover 5 is removed to have access to the vessel A.

It is noted also that in view of the fact that 40 the rim 8 of the closure 4 is beneath the rim portion of the closure 5, when desired, the two closures may be removed by simply lifting up on the rim 8 of the inner closure.

The term wiener steamer includes a cooking and steamer appliance generally, and the claims should be read in the light of my understanding.

Having thus described my invention, what I claim as new and desire to secure by Letters 50 Patent of the United States, is—

1. In a wiener steamer, comprising, a chamber, a partition dividing the chamber into compartments, an inner closure provided with means for closing one of the compartments, a flange formed on said means to contact with the partition, a tongue projecting from said flange and adapted to interlock the partition and said closure, and an outer closure for the chamber extending over and resting partly on the inner closure.

2. In a wiener steaming appliance, a base, a chamber carried thereby and adapted to hold articles of food, a partition in said chamber separating it into at least two compartments, an inner closure adapted to close the

upper end of one of the compartments of the said chamber and reversible upon the chamber in order to close the other compartment when the first compartment is not to be closed thereby, and an outer closure common to the two compartments and extending over the inner closure, the inner closure comprising a semi-circular body having a circular rim to fit over the upper end of the chamber, and the outer closure comprising a circular body having a rim fitting over and upon the rim of the inner closure.

In testimony whereof I affix my signature.

WILLIS W. HALE.
